UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

MACHINE FOR FORMING BEADED CAN BODIES.

Application filed July 30, 1920. Serial No. 400,201.

To all whom it may concern:

Be it known that I, PETER KRUSE, a citizen of the United States, residing in the borough of Brooklyn, county of Kings, city and State of New York, have invented certain new and useful Improvements in Machines for Forming Beaded Can Bodies, of which the following is a specification.

This invention relates to machines or devices for forming can bodies, tubes, or the like, especially beaded can bodies, tubes, or the like.

The invention provides a machine or a device especially suitable for can bodies or tubes of small diameter, and provides a horn wherein the construction is simple and strong, when made in small dimensions. The horn or device is especially advantageous as a part of a machine or device for forming beads, ribs, or the like, on can bodies or tubes of small diameter.

The invention further provides an advantageous combination of parts of a forming horn or mechanism, and of a beading or like horn or mechanism.

An embodiment of the invention is illustrated in the accompanying drawings, wherein—

Figure 1 is a longitudinal sectional view of a horn of a can body forming and beading machine, together with sufficient of the associated parts to illustrate the construction;

Figure 2 is a view generally similar to that in Figure 1, showing the parts in a different position;

Figure 3 is a detailed view, in elevation, of the group of segments forming part of the beading device or mechanism;

Figure 4 is an end view, from the right;

Figures 5, 6 and 7 are, respectively, sectional views, on the lines V—V, VI—VI and VII—VII, Figure 2; and

Figure 8 is an end view of a body forming and beading machine, showing certain parts used in conjunction with the horn at the beading station.

Referring to said drawings, A designates the horn as a whole, which may be, as here shown, a horn adapted to support a can body or tube in a plurality of working positions. In the position marked seaming position, the ends of a blank are wrapped around the horn by a suitable folding or wrapping mechanism (not shown), and the

lapped and usually interlocked edges bumped or pressed together, all of which is well known in the art. In the position marked beading position, the tubular can body may be formed with a bead or circular rib, adapted to stiffen the end of the can and form a shoulder for limiting a cap fitted thereon, when said body is completed in the form of a can or body, as, for example, a snuff box. B indicates a bracket or support for the horn, and C a slide for actuating certain parts of the horn mechanism, as hereinafter more fully explained. The slide C is conveniently guided on the bracket B, and is reciprocated by any suitable mechanism (not shown).

E designates a reciprocatory feed bar, having fingers e thereon, adapted to intermittently advance bodies or tubes along the horn.

The horn preferably comprises a tubular sleeve 10, attached, in suitable manner, to the bracket B.

Hinged upon the sleeve 10, as indicated at 12, preferably at or near the end of said sleeve, there are a plurality of segments 15, conforming, as a whole, to the contour of the tube or body on the horn.

The hinge is preferably formed by a rib 17 on the inner side of the several segments 15 fitting into a groove 18 in the sleeve 10. A spring, preferably a circular or spiral spring 20, encircles the segments 15, and holds the segments in hinged relation to the sleeve 10. A groove 22 in the segments is preferably provided for receiving the spring 20. The segments 15 are preferably drawn together or collapsed by a spring, preferably a circular spiral spring 25, encircling the segments, and preferably fitting in a groove 26.

Suitable means are provided for spreading or swinging outwardly the said segments around the hinge 12, said means being preferably a wedge 30, conveniently fitted upon a rod 32, passing through the sleeve 10, and through the circle or ring of segments 15.

When the machine or device is to be used for beading, means are provided for pressing or confining a can body or tube on the horn, in the vicinity of the segments 15, that is, at the beading position. This means is conveniently in the form of a plurality of radially movable segments or jaws 40, slideable in a bracket ring 42, and pressed in-

ward by means of a cam ring 44, having cam surfaces 45 adapted to contact with rolls 46 on the several jaws 40. Springs 47 may serve for drawing the jaws away from the horn, when this is permitted by the position of the cam ring 44.

A rod 49 serves for imparting properly timed short oscillations to the cam ring 44.

Complemental die and punch parts for 10 forming the rib or bead on the can body or tube are formed upon the segments 15 and the jaws 40. These die and punch parts are conveniently in the form of a rib or bead 50 on the segments 15, and a groove 51 in the 15 jaws.

At the seaming position, the sleeve 10 is conveniently formed with a block or expander piece 55, and means are provided for moving the said piece 55 in and out, to expand and collapse the horn at said position. These means are conveniently a plurality of complemental inclines 56, 57, these being conveniently formed directly upon the piece 55, and upon the rod 32, respectively. 20 Springs 58 in recesses 59, attached to the piece 55 and to the sleeve 10, serve to draw in the piece 55, so as to collapse the horn when this is permitted by the inclines 56, 57.

30 Operation.

The sheet metal or other blank is fed or placed over or under the horn in the seaming position (according to the position of the bumper and the design of the machine), 35 and is wrapped around the horn in said position, by well known means. The blank is usually formed with hooked edges, which hooked edges are lapped by the folding means. The expander slide C is thereupon 40 actuated to draw the rod 32 to the left, causing the inclines 56, 57 to press the expander piece 55 outward, thereby expanding or enlarging the tube or can body wrapped around the horn, so as to draw the hooks together. Complemental inclines 60 and 61, 45 on the expander slide C, and the rod 32, serve for imparting this movement to the rod 32. When the expander piece 55 has thus acted to draw together the hooked 50 edges of the body, the bumper presses the hooks together, so as to form a seam. The expander slide retracts, whereupon the rod 32 is pressed to the right, this being preferably accomplished by a spring 65, encircling the end of the rod 32, opposite the 55 wedge 30, said spring conveniently bearing, at one end, against an abutment 66, secured to the bracket B conveniently by bolts 67, the opposite end of the spring 65 bearing 60 against a shoulder 68 on the rod 32.

After the rod 32 has moved to the right, the springs 58 serve to draw in the expander piece 55. The feed finger e thereupon advances the can body or tube, either directly or by way of one or more idle positions, to

the beading position. In the beading position, when the rod 32 is pushed to the left by the expander slide C, the wedge 30 acts to spread the ring of segments 15, which rock or swing on the hinge 12, thereupon 70 bringing the segments against the inner side of the can body or tube. At the same time, the jaws 40 are pressed in against the can body or tube, by means of the cam ring 42, and the co-action of the beads or ribs 50 and 75 the grooved jaws 51 serves to form a circumferential bead on the can body or tube, which bead serves any desired purpose; usually that of limiting the movement of a cap on the end of said can body or tube, 80 when completed in the form of a box. The space around the horn is free and the horn has no peripheral projections exceeding the diameter of the tube or can body to be formed and beaded thereon, the can body or 85 tube therefore having no impediment to continuous movement in one direction from its position of seaming to its point of discharge from the horn.

When the rod 32 is returned, or moved 90 to the right, by the spring 65, the wedge 30 allows the spring 25 to draw together or collapse the segments, and jaws 40 are conveniently, at the same time, drawn away from the can body by means of the action of 95 the cam ring 44 and the springs 47. Thereupon, the beaded can body is ejected from the horn by a succeeding can body acted upon by a finger on the feed bar E.

Where the beading operation is performed on a device for forming the tubes or can bodies, it is conveniently combined with the seaming horn, as here shown. The mechanism at the beading position, however, can be used separately from the other 100 parts of the mechanism, and the horn at the beading position may have application in machines for performing other operations than beading.

The invention may receive other embodiments and applications than that herein specifically illustrated and described.

What is claimed is:

1. A horn for can machines, comprising hinged longitudinal segments, and means for moving said segments to swing them toward the inner sides of a can body, a series of exterior segments adapted to co-operate with said hinged segments to clamp a can body between them, and means for moving said exterior segments toward and from said horn said segments having complemental die and punch parts thereon.

2. A horn for can machines, comprising a sleeve, an expander part at one station or 125 part of this horn, and hinged longitudinal segments at one end of said sleeve, at another station, and means for operating said expander part and hinged segments, said horn being without projections beyond the cir- 130

- 5 cumference of the tube to be formed thereon, and the space around the horn being free, whereby said tube may have continuous movement in one direction from one position to the other, and off the horn, means exterior of and opposite said hinged sections, said hinged sections and exterior means having complementary means for forming a bead on an interposed can body.
- 10 3. A horn for can machines, comprising a sleeve, an expander part at one station or part of this horn, and hinged longitudinal segments at one end of said sleeve, at another station, and means for operating said expander part and hinged segments, said operating means comprising a rod passing through said sleeve, said horn being without projections beyond the circumference of the tube to be formed thereon, and the space around the horn being free, whereby said tube may have continuous movement in one direction from one position to the other, and off the horn, means exterior of and opposite said hinged sections, said hinged sections and exterior means having complementary means for forming a bead on an interposed can body.
- 15 4. A horn for can machines, comprising a sleeve, an expander part at one station or part of this horn, and hinged longitudinal segments at one end of said sleeve, at another station, and means for operating said expander part and hinged segments, said operating means comprising a rod passing through said sleeve, and a spring acting on said rod outside of said sleeve opposite the end with the hinged segments, said horn being without projections beyond the circumference of the tube to be formed thereon, and the space around the horn being free, whereby said tube may have continuous movement in one direction from one position to the other, and off the horn, means exterior of and opposite said hinged sections, said hinged sections and exterior means having complementary means for forming a bead on an interposed can body.
- 20 5. A horn for can machinery, comprising hinged longitudinal segments, means for moving said segments to swing them toward the inner sides of a can body, said horn having a part inward from said hinged segments at which the sheet may be wrapped around the horn to form a tube, said horn being without projections beyond the circumference of the tube to be formed thereon, and the space around the horn being free, whereby said tube may have continuous movement in one direction from one position to the other, and off the horn, means exterior of and opposite said hinged sections, said hinged sections and exterior means having complementary means for forming a bead on an interposed can body.
- 25 6. A horn for can machinery, comprising hinged longitudinal segments, means for moving said segments to swing them toward the inner sides of a can body, said horn having a part inward from said hinged segments at which the sheet may be wrapped around the horn to form a tube, said horn being without projections beyond the circumference of the tube to be formed thereon, and the space around the horn being free, whereby said tube may have continuous movement in one direction from one position to the other, and off the horn, means exterior of and opposite said hinged sections, said hinged sections and exterior means having complementary means for forming a bead on an interposed can body.
- 30 7. A horn for can machinery, comprising hinged longitudinal segments, means for moving said segments to swing them toward the inner sides of a can body, said horn having a part inward from said hinged segments at which the sheet may be wrapped around the horn to form a tube, said horn being without projections beyond the circumference of the tube to be formed thereon, and the space around the horn being free, whereby said tube may have continuous movement in one direction from one position to the other, and off the horn, a series of exterior segments adapted to co-operate with said hinged segments to clamp a can body between them, and means for moving said exterior segments toward and from said horn, said segments having complementary die and punch parts thereon.
